(57) **CLAIM**

The ornamental design for a tire for automobile, as shown and described.

DESCRIPTION

FIG. 1 is a front view of a tire for automobile showing my new design;

FIG. 2 is a rear view thereof; and,

FIG. 3 is a top view thereof, the bottom, left side and right side being the same.

The portions of the drawings illustrated in broken lines are directed to the environment of the design and form no part of the claimed design.

1 Claim, 3 Drawing Sheets

FIG. 1

FIG. 2

FIG. 3
